METAL TRANSFER SYSTEM

Herbert M. Short, Bridgeville, Pa., assignor to
 Aluminum Company of America, Pittsburgh,
 Pa., a corporation of Pennsylvania

Application February 11, 1949, Serial No. 75,819

2 Claims. (Cl. 266—38)

1

This invention relates to a metal transfer system or device particularly useful in the handling of those metals, such as aluminum or aluminum alloy, which form, on those molten surfaces which are exposed to the atmosphere, an oxide coating. During the transfer of such molten metal it is desirable to create conditions under which the oxide coating originally formed by the initial exposure of molten metal to the atmosphere is maintained and is not ruptured and consequently entrained in the flowing metal. Such conditions necessarily include a relatively quiet, non-turbulent flow of metal from splashing, cascading or like effects so that large areas of molten metal are not exposed to the atmosphere and so that the oxide film or skin formed on the exposed surfaces of the metal rests quietly thereon and is not continually drawn into the metal. The transfer system of the present invention is specifically designed to achieve such quiet, non-turbulent transfer and is useful not only in the handling of those metals which form such oxide coatings but also in the handling of any metal where a quiet flow of metal is desired from a source, such as a furnace, a pot or a crucible, to a receiving receptacle such as an ingot mold, a feed trough, a crucible, a holding pot or the like.

For convenience, and by way of showing a preferred example of one embodiment of the invention, reference will be made in the following description to the drawing, in which:

Fig. 1 is a longitudinal elevation, in cross section, through one form of the subject transfer system, shown as adapted to the transfer of metal from a holding furnace to a receiving trough;

Fig. 2 is a similar longitudinal elevation, in cross section, through one portion of the assembly shown in Fig. 1, some of the elements of the assembly being shown in another position; and

Fig. 3 is a top view of the portion of the transfer system shown in Fig. 2.

Referring to the drawing, the molten metal source or furnace 25 is shown in Fig. 1 as containing molten metal to the level A. Seated through and in sealed engagement with the wall of the furnace is a pouring spout 10, to which is attached a basin 11. Molten metal is indicated as held in said spout and basin to the level B. The end of the pouring spout which is seated through the wall of furnace 25 is shaped to form a restricted passage 15 through which metal may pass from the furnace into spout 10 and the basin 11. The passage 15 may be temporarily

2

sealed to prevent metal flow to the spout by any conventional device, such as the tap rod 16, and when the passage is open flow of metal therethrough may be controlled by any device. For convenient handling the tap rod 16 is here shown as supported by the cross bar 23. The basin 11 is provided with a downwardly extending discharge passage or nipple 13, provided with an orifice 14 through which molten metal may flow to a metal receiving receptacle, here shown as a trough 12. A sealing means, here shown as the rod 17, is mounted for vertical adjustment in block 19. The upper surface of rod 17 is threaded to operate in screw threads provided in block 19 and vertical adjustment is made by turning the rod 17 in the block 19. The closure rod 17 is so proportioned that its lower end will seat on the inner walls of nipple 13 to seal the passageway formed thereby and to thus prevent flow of molten metal from the basin 11 through the orifice 14 into the trough 12. A knob 18 may be provided at the upper end of the rod 17 to facilitate vertical adjustment thereof with respect to the block 19. Block 19 is supported by means of legs 20 on a buoyant float 21 shaped to rest within the basin 11. Lugs 22 attached to float 21 are positioned to extend over the wall of the basin 11 (best shown in Fig. 3) and are of a length such as will prevent the float 21 from contacting the bottom of basin 11 when no molten metal is present therein (the condition shown in Fig. 2).

Thus the floating valve assembly, including rod 17 and float 21, produces a sealing or opening of the metal delivery passage 13 by moving the rod 17 into sealing register with the orifice 14 as the metal ebbs in basin 11. Conversely, when the metal rises in basin 11 the float 21 is borne upwardly, thus moving rod 17 upwardly and away from sealing register with said orifice. It will be noted that the movement of the buoyant member 21 is limited, in that direction of movement which is caused by the ebb of the metal, by the action of lugs 22 or other movement limiting device.

At the beginning of a metal transfer operation the valve assembly is placed in the basin 11 in the position indicated in Fig. 2, the lugs 22 bearing on the wall of the basin 11 to hold the float 21 in a position above the floor of the basin. The rod 17 is vertically adjusted to seat over the orifice 14 to either close or materially restrict the orifice 14. For this purpose the operator may vertically adjust rod 17 in block 19. The operator then opens the spout passage 15, by with-

drawing tap rod 16, allowing metal to flow from the furnace 25, through spout 10 into the basin 11. It will be noted that, because of its position above the floor of the basin, the float 21 will not initially be buoyed by the molten metal passing into the spout and that consequently the closure element 17 will initially remain seated over the delivery orifice until such time as the rising level of molten metal in the spout reservoir causes the float 21 to rise, whereupon the closure element 17 will be borne upwards, thereby opening the delivery orifice 14. The weight of the float 21 and the parts supported thereby may be so adjusted that the closure element 17 does not free the metal delivery passage until the metal has arrived at a desired level in basin 11. Thereafter such level may be maintained by manipulation of the tap rod 16 in the restricted passage 15 to govern metal flow into the spout 10 from the furnace 25.

In the preferred device illustrated in the drawings it will be noted that the metal passage or nipple 13 is so proportioned as to extend to a point which will be below the level C of metal in the trough 12 so that the discharge port or orifice 14 will lie below the metal level C. Thus when flow of metal is initiated in the system, the metal issuing from orifice 14 will not drop a great distance to the floor of trough 12 and, once the metal level C is established in the trough 12, the discharge of metal through orifice 14 will be below the level of the metal in the trough.

Among the advantages secured by the use of the transfer system of this invention is the maintenance of the desired metal levels by operative adjustment at a single point. Thus in the device above described operative adjustment of the tap rod 16 will maintain constant the metal level B in the basin 11 and the metal level C in the trough 12. Moreover it will be apparent that the basin and trough arrangement shown may be multiplied, where conditions require delivery of metal to more than one trough, without requiring the necessity for adjustment except at the point of flow of the metal from the metal source into the basin. Moreover, once metal flow has begun and the metal levels have been established, the transfer of the metal will proceed quietly, without turbulence or cascading and any oxide skin formed on the exposed surfaces at metal levels B and C will tend to remain quietly on such surfaces and will not be readily entrained by metal flowing through the basin and the trough.

Having thus described my invention, I claim:

1. In an apparatus for the quiet transfer of

molten metal comprising, in combination, a metal transfer basin positioned to receive molten metal from a source thereof, a metal receiving receptacle positioned below said basin to receive discharge of metal from said basin and means for controlling the discharge of metal from said basin to said receptacle, the improvements consisting of walls formed to define a downwardly extending metal discharge orifice in the bottom of said basin, a buoyant valve assembly comprising a float member and a vertically adjustable downwardly extending sealing member mounted on said float member, said assembly being shaped to fit within said basin and positioned in said basin to float on metal contained therein with the sealing member of said assembly in vertical alignment with said orifice and means disposed to limit the vertical downward movement of said float member with said metal to a point above the bottom of said basin.

2. In an apparatus for the quiet transfer of molten metal comprising, in combination, a metal transfer basin positioned to receive molten metal from a source thereof, a metal receiving receptacle positioned below said basin to receive discharge of metal from said basin and means for controlling the discharge of metal from said basin to said receptacle, the improvements consisting of walls formed to define a downwardly extending metal discharge orifice in the bottom of said basin, a buoyant valve assembly comprising a float member and a vertically adjustable downwardly extending sealing member mounted on said float member, said assembly being shaped to fit within said basin and positioned in said basin to float on metal contained therein with the sealing member of said assembly in vertical alignment with said orifice and means disposed to limit the vertical downward movement of said float member with said metal to a point above the bottom of said basin.
